United States Patent Office.

TIMOTHY G. PHELPS, OF BELMONT, CALIFORNIA.

Letters Patent No. 93,000, dated July 27, 1869.

IMPROVED SCRAPER.

The Schedule referred to in these Letters Patent and making part of the same.

To all whom it may concern:

Be it known that I, TIMOTHY G. PHELPS, of Belmont, in the county of San Mateo, and State of California, have invented certain new and useful Improvements in Machines for Constructing Highways, Turnpikes, and Railroads; and I do hereby declare that the following is a full and exact description of the same, reference being had to the accompanying drawings, and to the letters of reference marked theron.

The nature of my invention is to provide a reversible scraper, for the more rapid and cheap construction of highways, turnpikes, and railroads, so that the crown of the street or roadway may be formed on the line of travel by the machine, without the necessity of hauling the earth transversely from side to side.

To accomplish this object, I employ a curved scraper, that is connected by hooks and eyes to the rear of a stout frame, which is mounted on wheels.

A flat, curved bar extends around the back of the scraper, conforming to its shape, and acting as a brace.

The bar also forms a semicircular plate between the scraper and frame.

Holes are pierced in the plate for connecting and extension-rods.

A flat bar is pivoted to the top of the scraper, and extends to the rear cross-beam of the frame, passing under the semicircular plate, to which it is connected by a strap.

By this construction, the scraper is changed to run at the angle desired.

Referring to the drawings for a better illustration of my device, the figure represented is a plan or top view of my machine.

A is a stout frame, mounted on two driving-wheels, and bolted to the axle and neap.

To the rear end of the frame, on a plane with the top of the axle, is bolted a stout cross-beam, B, and through it eye-bolts *a a' a a* pass, for connecting the scraper.

The scraper C may be made of iron or steel, and have the desired curvature.

If it is made of iron or wood, a shoe or share, D, may be attached, to give a better cutting-edge.

By means of the flat bar, a semicircular turn-plate, E, is formed between the cross-beam of the frame and top of the scraper, the arms of which extend around the back of, and are bolted to the scraper.

Between these arms is also bolted a brace, F, the top of which forms a pivot, F', for the transverse draught-bar G, which passes under the turn-plate, to

which it is connected by a strap, G', and hooks into the eye-bolt *a* on the cross-beam of the frame.

At each end of the scraper are bolted braces H H, which extend to the turn-plate, and to which they are also attached by bolts. By this means the scraper is firmly braced, and no ordinary strain can affect it on the line of travel, even if it is made of thin boiler-iron.

Each of the side-braces is pierced about midway, for the connecting and extension-rods I I' I"; and when it becomes necessary to change the angle of the scraper from one side of the road to the other, the rod I is removed to the opposite end, to occupy the position of the extension-rod I'; and one end of this rod is hooked in the eye-bolt adjoining, and the other end is placed in one of the eye-holes *b* on the turn-plate, after the transverse extension-rod I" has been removed.

The extension-rod I" is now placed in the eye-bolt and eye-hole, which the stay-rod I before occupied, and the desired angle to the scraper is obtained.

The scraper, however, can be made to run more or less right or left obliquely, by lengthening or shortening the rod I I', and changing the hook on the end of the rod I", from one graduated hole *b b*, to another on the turn-plate.

This rod acts as an oblique strengthening-rod, and prevents the scraper from swaying or moving laterally; and another rod of the like character may be employed at the opposite end, the one crossing the other on the turn-plate.

In constructing railroads and turnpikes, where the ditch is to be cut deep, the cross-beam at the rear of the frame may be lengthened, and extend beyond the reach of the wheels, and to it be attached extra motive-power, to assist in the side or end-draught.

This end of the scraper may also be weighed; usually the weight of one man on the handles *c c* will be sufficient.

Having thus described my invention, What I claim, and desire to secure by Letters Patent, is—

The scraper described, consisting essentially of the carriage A, draught-bar G, semicircular turn-plate E, and scraper C, the whole being combined substantially in the manner and for the purpose described.

In witness whereof, I have hereunto set my hand and seal.

TIMOTHY G. PHELPS. [L. S.]
